APPARATUS FOR CONTROLLING WEBS

Andrew King, Narberth, Pa.

Application May 19, 1931, Serial No. 338,456

17 Claims. (Cl. 242—76)

242 - Wimberly
76   *Graves & G.*

My invention relates to apparatus for controlling the web in a printing press or other similar machine in which paper or other similar material is fed. More particularly, my invention relates to improved mechanism and method of controlling the lateral deviations of a web of paper from its normal path.

The object of this invention is to provide a novel means for keeping paper or other material, such as the paper in a newspaper printing press, etc., usually called the web, running past a given place at a given distance from a fixed point at the side.

Another object is to provide such novel means as will keep the web closely in line and not, as is usually the case, correct the position after it has shown visual evidence of having run out to the side.

Another object is to provide means for accomplishing the above objects which shall be entirely automatic, and require no overseeing whatever. A more specific object of my invention is to provide an apparatus for correcting lateral deviations of a web in which a detector, spaced from a point of control, operates intermittently and, more specifically, at such times that it ceases operation prior to the time that a change in position of the web at the point of control is indicated at the point at which the detector is positioned.

A further specific object of my invention is to provide a method of controlling lateral deviations of a web through the practice of which hunting is eliminated.

Another specific object of my invention is to provide a method of an apparatus for controlling lateral deviations of a web by the practice and use of which, in a large percentage of cases, a change in position of the web will not be caused by temporary changes in the position (i. e. tears and notches) of an edge of the web.

I attain these and other objects by the means shown in the accompanying drawings and in which:

45 Fig. 1 is a diagrammatic view of the device.

Fig. 2 is a section thru the detector showing the arrangement of the lamp, the photoelectric cell and the slots.

Fig. 3 is a diagram of the timer 41 shown in 50 Fig. 1 in perspective.

Fig. 4 is a section of Fig. 2 showing the relation between the slots 44, the edge of the web and the photocell 21.

Referring to the drawings, 1 is the web coming from the roll 2 passing over the roller 3 and

between the drag rolls 4 and 5. The end 6 of the web may go to a printing press, a folding machine or other mechanism into which the web must be fed straight.

The roll 2 is mounted on a support 7 capable of being moved laterally to either side thru the screw 8, the worm wheel 9 and the worm 10 by the motor 11 which is shown here as a D. C. reversible motor. A drive of this kind is in common use at present for this purpose but the controls are now operated manually.

The direction of rotation of the motor 11 is controlled by the reversing switch 12 which is controlled by the relay 13 which, in turn, is controlled by the detector unit 14 thru the relay 15.

The detector unit 14 comprises a light sensitive unit 16 of which the relay 15 has been placed separately in the diagram in order to be able to follow its operation in making the contacts 17 and 18 when the light from the lamps 19 and 20 strikes the photoelectric cell 21, Fig. 2.

Driven by the drag roll 4 from the pinion 22 is the gear 23 which is rigidly attached to the shaft 24 on which are mounted the drums 25, 26, 27 and 28 and the slip ring 28 which is insulated from the shaft 24 by the fibre bushing 28a. The drums are made of a nonconducting material and provided with contact shoes 29, 30, 31, and 32. The slip ring 28 and the shoes 29, 30, 31, and 32 are connected together electrically by the connector 34. Making contact with the drums are the brushes 35, 36, 37, 38, 39, and 40 which distribute the current where and when required.

In the detector unit 14 the lamps 19 and 20 are enclosed in boxes 42 and 43 respectively in the bottom of which are the slots 44 and 45 respectively which are located with reference to the edge of the web 1 so that the slot 44 is inside of the edge of the web and the slot 45 is just over the edge with a narrow space between the two slots, the width of the slot and the space between depending on how closely it is desired to control the web.

Located below the above slots is the slot 46 in the top of the box 47 in which is located the photoelectric cell 21 together with the amplifier and the balance of the unit. This unit is a commercial unit and its construction is not part of this invention. The type used here is that in which the current passing thru the unit increases with the increase of light but with a little modification the type in which the current increases when the light is cut off could be used. It will be seen that the light from either of the

boxes 42 or 43 will cause the photoelectric cell to act and close the relay 18.

Attached adjacent to and operated by the worm wheel 8 is the timer 41 Figs. 1 and 3, 5 which controls the amount of rotation of the worm wheel 8 and therefore the amount of lateral movement of the spider 1.

The timer consists of two arms of iron 48 and 49 located on each side of the worm wheel 8 and pivoted to the yoke 50 at 51 and 52 respectively with the electromagnet 53 between them so that when the magnet 53 is energized the arms 48 and 49 will pinch and adhere to the worm wheel 8. The yoke 50 is pivoted on the 15 bar 51 which is suitably supported, but this means is not shown as it would unnecessarily confuse the drawings. The yoke 50 is provided with an upstanding finger 55 held in a vertical position by the opposing springs 56 and 57. Pivoted on the bars 58 and 59 are the depending fingers 60 and 61 which are provided with electrical contact points 62 and 63 insulated from the said fingers by the insulators 64 and 65. The contact points are held in contact by the spring 66, and the pivotal movement of the said finger is limited by the stop pins 67 and 68 which allow the point to come in contact but which limit the movement of the said fingers. Located on each side of the upstanding finger 55 and 25 mounted in the fingers 60 and 61 are the screws 69 and 70 against which the finger 55 contacts when it breaks the contact 62 or 63 when the worm wheel 8 has rotated the predetermined 30 amount to either side.

35 The reversing switch 12 is operated by the sole-noids 81 and 82 which are operated thru the relay 18.

The wiring diagram has been numbered at all 40 points of junction as well as at terminals to facilitate explanations.

The operation of the device is as follows, and this explanation will, at the same time, constitute an explanation of the wiring diagram:—

The detector unit is assumed to be properly 45 located with reference to the edge of the web to be controlled and placed at a given distance from the roll 2. This distance depends on a large 50 number of things and it may be any distance but the ratio of the gears 22 and 23 is governed by this distance as it is important to allow enough 55 web to pass by the detector 14 after each reading to show the effect of the correction at the detector before shifting the roll 2 again. Therefore, the drums on the shaft 24 are driven at such a ratio 60 to the web that the web must travel from the roll 2 to the detector 14 in the time elapsing between contacts. In many cases where frequent control is not necessary this ratio can be much greater and the web may travel two or three 65 times the distance before another contact is made.

As the shaft 24 rotates it carries the drums 25, 65 26, 27, and 28 with it and immediately after moving in the direction of the arrows from the 70 position shown in Fig. 1 the shoes 29 and 31 come under the brushes 35 and 37 respectively which energizes the magnet 53 on the timer 41 and turns on the lamp 19 in the box 42. Immediately thereafter the shoe 32 comes under the brush 38 which 75 makes the line 39-44 alive. If the paper is in the proper position it covers the slot 44, no light passes thru to the photoelectric cell and nothing happens, but if the paper is off to the left in Figs. 1 and 2 the light will fall on the photoelectric cell and the relay 18 will close the contacts 17 and

18 which in turn will connect terminals 83 and 84, open 85 and 86, and cause the solenoid 87 to pull the reversing switch 12 to the left in Fig. 1 which will turn on the motor 11 and cause the worm wheel 8 to rotate and turn the screw 8, moving the support 7 and the roll 2 toward the right in Fig. 1 to an amount determined by trial and set by the screws 69 and 70. In this case it would contact with the screw 78 and after the worm wheel 8 has made the necessary part of a revolution the finger 55 will push on the screw 70, break the contacts 62 and 63 and stop the motor.

As soon as the shoes 29, 31, and 32 have gotten out of contact with the brushes 35, 37, and 39, respectively, the lines connected therewith will become dead and all parts resume their normal 15 positions ready for the next part of the cycle which determines whether or not the paper is too far to the right.

Further rotation of the shaft 24 causes the 20 shoes 38 and 31 to make contact with the brushes 35 and 36 respectively, lighting the lamp 20 in the box 43 which, if the web is in the central position, allows the light to pass thru the slot 45 and strike the photoelectric cell 21 and close the 25 contacts 17 and 18 which opens contacts 85 and 86. This closes 83 and 84 again but as this line is open nothing occurs. Immediately thereafter the shoe 32 contacts with the brush 38 which energizes the line 39-45 but, as this has just been 30 opened, nothing happens. If, however, the web is off to the right in Figs. 1 and 2 the slot 45 is covered, the relay 18 is not operated and the circuit 38, 85, 86, 82, 85, 86 is therefore closed and causes the magnet 82 to operate the reversing switch 12 and turn on the motor so as to rotate the worm wheel to move the roll 2 to the left in Fig. 1. Contact of the shoe 30 with the brush 38 has energized the magnet 53 as in the preceding case.

It will be seen that when the web rides to either side it will cause a movement of the roll 2 in the opposite direction at periodic intervals so long as the web is off to the side. Both the detecting and the correcting are done at intervals in order 45 to give the correcting means time to correct and the detecting means time to see if the proper correction has been made before making another correction. From what has already been said it will be apparent that the timer is on only when 50 light from lamp 19 reaches photocell 21 or when light from lamp 20 cannot reach photocell 21. Therefore any notches in the edge of the paper will actuate the timer only when the notch in the paper and the contact or the commutator coincide, which will be only occasionally. If this should occur the operation of the motor 11 will last only for the fraction of a second and not enough to affect the position of the paper.

I am aware that an automatic web control 60 is not new in itself and I therefore do not claim such an invention broadly.

Various modifications may be made in the above described embodiment of my invention without departing from the spirit and scope thereof as 65 set forth in the following claims:

What I claim is:

1. The combination of a web mounted on supporting means provided with mechanism for moving said supporting means laterally, a source of 70 light capable of being interrupted or intercepted by said web, and means brought into action when said web deviates from its allotted path whereby the light causes the moving mechanism to move said supporting means laterally a predetermined 75

amount, said amount being independent of the deviation of said web.

2. The combination of a web, means for supporting said web, means for moving said web laterally, means located at one edge provided with two lights which are capable of being independently turned on at intervals depending on the web movement, means for controlling the lights, means actuated thru these lights to actuate said means for moving the web laterally in either direction by moving said supporting means and means for limiting the amount by which said moving means shall act.

3. The combination of a web, means for supporting said web capable of moving laterally in either direction, means provided with two slots thru which is passed light from two light sources, respectively at intervals but not at the same time, means for turning on either light alternately, light sensitive means capable of receiving the light from either light source and which operates said light sensitive means for making a circuit when light strikes it, switching means controlling the means for moving the web laterally and means including said light sensitive means whereby said switching means causes the lateral movement of the supporting means to one side when the light passes thru the first of said slots and to the other side if the light in the second named slot is intercepted.

4. The combination of a web, means for supporting said web and moving it laterally, means provided with two slots one of which normally lies over the web and the other lies directly out side of the edge of the web, means whereby light can be directed first to one and then to the other of said slots, light sensitive means capable of receiving light thru either slot, two sets of circuits controlled by said light sensitive means, means operated by said light sensitive means when the light strikes it to open one of said circuits and close the other and means controlled by these circuits for operating said lateral moving means to one side when the light passes thru the first named slot and to the other side when the light in the second named slot is intercepted by said web.

5. The combination of a longitudinally moving web, means for moving said web laterally in either direction, a series of electrical circuits, a series of commutators and brushes for controlling said circuits said commutators being rotated proportionately to the movement of said web and constituting a timing means, means for controlling the amount of said lateral movement so that said web can move laterally only a predetermined amount each time it is moved, two light sources each located over a slot, one of said light sources and slot being just past the edge of said web and the other light and slot located just inside of the edge of said web; light sensitive means capable of receiving light from both of said light sources and means whereby said light sensitive means, thru the rotation of said commutators under said brushes energizes one of said circuits and causes said means for moving said web laterally to move said web to one side when the light from the light source which is located above the slot located past the edge of said web is blocked off by said web and further rotation of said commutators energizes another circuit and causes said means for moving said web laterally to move said web to the other side when the light from the second named light source strikes said light sensitive

means thru the other of said slots when said slot is uncovered by said web.

6. The combination of a longitudinally moving web, current controlling means operating at a fixed relative speed to said longitudinal movement, means for moving said web laterally a predetermined amount each time the said moving means is operated and light sensitive means operated by suitable light sources located at the edge of said web for determining if said web has deviated from its allotted path, said light sensitive means being rendered operative thru said light sources and said current control thereby causing said means for moving said web laterally to operate and move said web back toward its allotted path.

7. The combination of a web capable of moving longitudinally, which it is required to keep in line; current controlling means operating at a fixed relative speed to said longitudinal movement, means for moving said web laterally a predetermined amount at intervals, light source and light sensitive means made operative at intervals by said current control to cause said web to move laterally back toward its normal position thru the operation of said means for moving said web laterally.

8. The combination of a web capable of moving longitudinally and means for moving said web laterally a predetermined amount when said web moves out of its proper path to bring said web back into position, said means including lights and light sensitive means, means by which said lights and light sensitive means are rendered operative at intervals proportional to the longitudinal movement of said web, control circuits operated thru said lights and light sensitive means by the lateral movement of said web out of its path and means for limiting the amount by which said web can be moved back to its proper path in any one operation.

9. In combination with a support for a roll of material from which a web is being drawn, means for moving said support laterally, a single photoelectric cell actuated by the interception and failure to intercept light rays by movement of said web away from its normal path, and means, responsive to the actuation of said cell, for actuating said support moving means.

10. In combination with a support for a roll of material from which a continuous web is being drawn, means for moving said support laterally predetermined amounts within greater fixed limits, and means, responsive to deviations of said web from its normal path, for causing said moving means to move one only of said predetermined amounts until the effect of said movement is reflected in the position of the web at the place where said last named means is positioned.

11. In combination with a support for a roll of paper from which a continuous web is being withdrawn, means for moving said support laterally; lamps; means for successively lighting and darkening said lamps; and means, responsive to said lamps, for starting said moving means.

12. In combination with a support for a roll of paper from which a continuous web is being withdrawn, means for moving said support laterally; lamps; means or alternately lighting and darkening said lamps successively; and means responsive to each of said lamps, for starting said moving means.

13. In combination with a support for a roll of paper from which a continuous web is being withdrawn; means for moving said support laterally

with respect to the normal path thereof; lamps; means for alternately lighting and turning off said lamps successively; light sensitive means positioned to react to light rays from said lamps, said 5 light sensitive means comprising means for closing a circuit; and means actuated by said circuit for actuating said moving means.

14. In combination with a support for a roll of paper from which a continuous web of paper is 10 being withdrawn, means including a motor for moving said support laterally with respect to the normal path of said web; means for stopping said motor after said support has been moved a predetermined distance; means for starting said 15 motor when said web diverges from its normal path; and means for rendering said last named means inoperative except at predetermined times, the time between the operative periods varying with the speed of the web.

15. In combination with a support for a roll of material from which a web is being drawn, means 20 for moving said support laterally, a light sensitive means, means for causing light rays to fall upon said light sensitive means, said light sensitive 25 means being actuated by the action of an edge of said web in intercepting and failing to intercept said light rays, means for periodically interrupting said light rays other than by said edge,

and means responsive to the actuation of said light sensitive means for actuating said light responsive means.

16. In means for guiding longitudinally moving webs, the combination of supporting means for said webs, means for moving said supporting means laterally by fixed amounts, means responsive to the movement out of a predetermined path of an edge of said web for detecting lateral deviations thereof, means rendering said last named means operative only after the effect on the web of moving said support by one of said fixed amounts is reflected at the position of said detecting means, and means responsive to said detecting means for actuating said support moving means.

17. In means for guiding a longitudinally moving web, the combination of a support for said web, means for moving said support laterally, means for detecting lateral deviations of said web, 20 means rendering said detecting means operative only after the effect of the last movement of the support moving means is reflected in the position of the web at the point where said detecting means is located, and means responsive to said detecting means for actuating said support moving means.

ANDREW KING.
